UNITED STATES PATENT OFFICE.

LOGAN WILLARD MULFORD, OF LONG ISLAND CITY, NEW YORK.

SKYLIGHT AND FLOORLIGHT CONSTRUCTION.

Application filed May 25, 1925. Serial No. 32,625.

My invention relates to a novel skylight or floorlight construction, wherein I employ lens holders or metal shields of a novel construction having outer walls, which converge downwardly and are provided with inner upwardly extending inwardly converging flanges upon the upper edges of which are seated the lenses or glass units, preferably of rolled, wired, annealed glass, 10 the V-shaped inner seat which is formed between the outer and inner walls of the lens holders forming a pocket for the reception of sealing and cushioning material, which also waterproofs all points of glass contact, while the outer surface of the inner 15 inclined lens supporting flange is protected by a mass of concrete, whose upper edge is coincident with the top of said inner flange and the bottom of the wired rolled, annealed 20 glass unit or lens whereby the lens holders or metal shields are entirely concealed and protected by the cement and will not be liable to rust, corrode or deteriorate under any condition of use.

My invention further consists of a novel manner and method of assembling the lens 25 holders or metal shields, the rolled, wired, or annealed glass lenses and the templates below them whereby when the concrete is poured into said templates it will not only surround the contiguous outer walls of the lens holders and will not only engage the beads therein, but said concrete will also flow upwardly around the rounded edge and 30 the contiguous outer wall of the lens supporting flange, so that the parts after the concrete has set will be effectively protected from rust or corrosion.

It further consists of other novel features 35 of construction and advantage, all as will be hereinafter described and pointed out in the claim appended hereto.

For the purpose of illustrating my invention, I have shown in the accompanying 40 drawings forms thereof which are at present preferred by me, since they will give in practice satisfactory and reliable results although it is to be understood that the various instrumentalities of which my invention consists can be variously arranged 45 and organized and that my invention is not limited to the precise arrangement and organization of these instrumentalities as herein shown and described.

Figure 1 represents a perspective view of

a lens holder in detached position embodying my invention.

Figure 2 represents on an enlarged scale, a sectional perspective view showing the manner of assembling the lens holders, the 60 rolled, wired, annealed glass lenses and the templates prior to the pouring of the concrete.

Figure 3 represents on an enlarged scale, a vertical sectional view of a portion of the 65 finished frame, showing particularly the concrete as inclosing and sealing the surfaces of the inner inclined lens supporting flange.

Similar numerals of reference indicate 70 corresponding parts in the figures.

In carrying out my invention in the production of my novel product, I employ a lens holder 1 of rectangular or other contour, having the downwardly and inwardly 75 converging side walls 2, whose lower edges are rounded as at 3, and provided with the upwardly extending inner lip or flange 4, whereby a V-shaped inner pocket 5 is produced, the extent and position of said pocket 80 being best understood from Figures 2 and 4. The upper edge of the flange 4 which is continuous and extends entirely around the lens holder, as will be understood from Figure 1, serves as a support for the lens of 85 rolled or wired glass 6, the wire mesh therein being indicated at 7, and being omitted if desired. 8 designates the sealing compound which occupies the space above the pocket 5, and effectively incloses the edges 90 of the wired glass lens 6.

9 designates the concrete, and 10 the reinforcing bars therein, it being noted that the upper outer surface 11 of the inclined flange 4 of the lens holder is completely surrounded by the cement at the points 12. This construction or collocation of the concrete with respect to the lens holder is effected by the template 13 made in two sections 14 split at the point 15, as seen in 100 Figure 2.

In the assembly of the elements producing my novel device, the lens holders or metal shields 1 are arranged substantially as seen in Figure 2, and the rolled or wired glass, 105 annealed lenses or units are placed in position upon the top edges of the inner flanges 4.

The reinforcements 10, which in practice are square steel rods extending longitudinal- 110

ly and transversely and of the proper sizes required for the various spans and the template sections 14, having been placed in position, the concrete 9 is next poured into the templates and after the concrete has set, the assembled elements prior to the removal of the templates will appear as seen in Figure 2, the sealing compound or cushion 8 having been poured into place at any suitable stage.

Upon the removal of the template sections 14, the parts will appear as seen in Figure 3, whereby it will be seen that the mass of concrete at the outer top portions as indicated at 12, completely encloses the outer surfaces 11 of the lens supporting flange 4 so that the entire surface of the lens holder and particularly said lens supporting flange 4 is entirely concealed and surrounded on its under side by the concrete, so that all liability of rust, corrosion and deterioration of the lens holder by exposure to the air is entirely obviated.

The metal shields or lens holders 1 in practice entirely surround each lens or wired glass unit 6 for its full depth, thereby providing a perfect protection against pressure of the concrete caused by expansion.

The lenses or glass units 6 are composed either of rolled or wired, annealed glass, which can be quickly replaced for convenience of making repairs with unskilled labor, said lenses or glass units 6 being in practice cut from either rolled, annealed glass or annealed, rolled, wired glass, which are cut to the desired contour at any desired stage in the manufacture of the sheet.

By my present construction and by the utilization of rolled, annealed wired, glass lenses having the characteristics described, a much stronger and more durable construction than heretofore is produced, and if a lens becomes shattered or broken it can be removed from its lens holder or metal shield by unskilled labor and readily replaced with a new one, so that the efficiency and durability of the construction can at all times be maintained at a minimum of cost. The rolled, annealed lenses can be removed without injuring the reinforced concrete frame-

work, since said lenses are carried by their respective metallic lens holders, which are not liable to injury when a broken glass is being removed.

The wired glass lenses 6 can be made from waste from rolled annealed sheets, for which at the present time there is no use, and the rolled sheet glass itself is much cheaper than pressed or molded glass, and in addition the rolled sheet glass being of a more uniform thickness enables a more uniform annealing than can be obtained in pressed or molded glass, which is usually of uneven thickness and contour.

The method of construction, whereby the concrete is caused entirely to surround the contiguous portions of the shield 1, particularly the flange 4, enables me to produce a superior character of work, and there are no parts of the flange 4 exposed to the air, so that the liability of rust and corrosion thereof is entirely obviated. The ribs or beads 16 are effectively interlocked in the concrete as is evident.

It will now be apparent that I have devised a novel and useful skylight and floor-light construction, which embodies the features of advantage enumerated as desirable in the statement of the invention and the above description, and while I have, in the present instance, shown and described preferred embodiments thereof which will give in practice satisfactory and reliable results, it is to be understood that the same are susceptible of modification in various particulars without departing from the spirit or scope of the invention or sacrificing any of its advantages.

Having thus described my invention, what I claim as new and desire to secure by Letters Patent, is:

The herein-described skylight, sidewalk, or floor-light construction, which consists of a metal lens holder, a rolled annealed glass lens supported thereon, and a bottom covering of concrete completely covering the bottom of said lens holder and extending to the bottom of said lens, whereby corrosion of said lens holder is prevented.

LOGAN WILLARD MULFORD.
